WILLIAM F. CONVERSE, OF HARRISON, OHIO.

Letters Patent No. 77,589, dated May 5, 1868.

IMPROVEMENT IN PORTABLE FENCE.

The Schedule referred to in these Letters Patent and making part of the same.

TO WHOM IT MAY CONCERN:

Be it known that I, WILLIAM F. CONVERSE, of Harrison, Hamilton county, Ohio, have invented a new and useful Portable Fence; and I do hereby declare the following to be a full, clear, and exact description of the same, reference being had to the accompanying drawings, making part of this specification.

My invention relates to the class of portable fences which comprise a series of panels connected together in a zigzag or "worm" form, and consists in devices for rapidly and cheaply yet securely uniting the consecutive panels.

Figure 1 is a perspective view showing two panels secured by my fastening.

Figure 2 is a top view of the same.

Figures 3 and 4 are enlarged horizontal sections of a joint, showing the mode of applying my hooks and key respectively.

Figure 5 is a horizontal section of a corner.

Figures 6, 7, and 8, represent modifications of my fastening.

A A' represent two contiguous panels set together at an obtuse angle. B B' are two S-formed hooks, which being slipped through between the battens C C', have their curved extremities engaged around the edges of the battens, as shown in fig. 3. The said hooks having been thus inserted, are made permanently secure, and at the same time the panels are retained immovably in their proper zigzag position, by the insertion from above of a key, D, whose taper corresponds to the angle of the panels, and which has a head, d, to prevent its escape endwise. In practice, I use four such hooks, and two such keys at each joint, as clearly shown in fig. 1.

When it is desired to unite two panels cornerwise or at right angles, I use a piece of wire, which I call the T, (see E, fig. 5,) which being bent at its middle so as to form a small circle, e, and thence being contiguous and parallel, I insert the two ends through both posts, and curve the same into the form of the two opposite hooks e' e'', which engage around two of the battens, in the manner shown in fig. 5. Figs. 6, 7, and 8, exhibit inferior modifications of my hooking-devices, and Figure 9 shows a modification of my key, in which barbs d' perform the duty of the head d. A still inferior modification may have a plain wooden key or wedge, in combination with my hooks of either form, and it is also obvious that I can entirely dispense with keys, for the panels being carefully abutted, the several parts are securely held in position.

The key when of my improved form, whether barbed or headed, is preferably inserted from the top or bottom, and driven sidewise down or up the joint, as the case may be.

I claim herein as new, and of my invention—

1. The headed wedge-form key D, constructed and applied, substantially as and for the purpose set forth.
2. The paired hooks B B', in the described combination with two contiguous panels.

In testimony of which invention, I hereunto set my hand.

WILLIAM F. CONVERSE.
